UNITED STATES PATENT OFFICE.

CLARENCE I. GLASSBROOK, OF SALT LAKE CITY, UTAH.

ORE-CONCENTRATOR.

1,083,531.

Specification of Letters Patent.

Patented Jan. 6, 1914.

Application filed December 23, 1912. Serial No. 738,314.

To all whom it may concern:

Be it known that I, CLARENCE I. GLASSBROOK, a citizen of the United States, residing at Salt Lake City, in the county of Salt Lake and State of Utah, have invented certain new and useful Improvements in Ore-Concentrators, of which the following is a specification.

This invention relates to certain new and useful improvements in machines designed for the concentration of ore, and the same consists, essentially, in providing a concentrating table with a surface composed of several connected and continuous planes, each adapted to perform a separate and distinct part in the process of concentrating a flowing body of mineral pulp.

The invention further consists, of a concentrating table having a surface composed of a stratifying plane, a succeeding substantially level bedding and discharging plane, a plane succeeding the discharging plane and adapted to resist or hinder the progression of material received from the discharging plane, and a dressing plane succeeding the resisting plane.

The invention further consists, in providing the surface of the concentrating table with a portion intermediate of its ends which is level longitudinally and transversely and which serves as a discharge plane for the separated material.

The invention also consists, in means for adjusting the inclination of the planes at opposite ends of the table, and in the parts and the construction, arrangements and combinations of parts which I will hereinafter describe and claim.

In the accompanying drawings forming part of this specification and in which similar letters of reference indicate like parts in the several views, Figure 1 is a plan view of a concentrating table embodying the salient features of my invention. Fig. 2 is a similar view of a table of modified form, showing longitudinally extending channels or overflow openings in the intermediate plane, and showing channels in the plane at the tail end of the table. Fig. 3 is a side elevation of the concentrator showing means for imparting a reciprocating motion thereto. Fig. 4 is an end view of the tail end of the table. Fig. 5 is a cross sectional view on the line, X—X of Fig. 2. Fig. 6 is a cross sectional view on the line Y—Y of Fig. 1. Fig. 7 is a detail illustrating the ad-

justment of the inclination of the discharge plane and its connecting retarding plane. Fig. 8 is a sectional detail of a modification to be hereinafter referred to.

In carrying out my invention I construct a table, T, of suitable material and of any desired length and width, said table being of the type adapted to be reciprocated and to this end the table is mounted at its ends and intermediate portions upon suitable rockers, R, which, in the illustrated embodiment of the invention may be of the type shown, described and claimed in my prior Patent Number 1,088,871, dated September 17, 1912. In order that such a table may be reciprocated, the head end thereof will be connected with some suitable form of head mechanism, shown generally at H for imparting reciprocable movement and in Fig. 3, I desire it understood that the salient features of the present invention do not relate to the head mechanism, but to the arrangement of the bed or working surface of the table, and, therefore, the present invention is not limited to any particular mechanism for imparting reciprocating movement to the table, or to any particular manner of mounting the table so that it may be reciprocated, as the novel bed or working surface of the table, which is the essential feature of my present invention, may be used in other relations and with other means for mounting and reciprocating the table, without departing from the spirit of the invention.

As shown in Fig. 1, the concentrating table has its bed or working surface, composed of four associated planes or divisions, each plane succeeding another and each plane performing a separate and distinct part in the operation, which I will herein-after describe.

At the head end of the table is mounted some appropriate feed box or distributor, F, from which the pulp or ore to be concentrated is fed upon the upper end of the long inclined plane, A, this plane representing one of the divisions or planes of the table, and the distributor being designed to feed pulp uniformly across the table at or near the upper or head end of the said plane.

The table is provided with appropriate sides, 2, which extend above the level of the concentrating surface, but at an intermediate portion of these sides corresponding to an intermediate plane, B, which I will

hereinafter specifically refer to, the sides are cut away or reduced in height, as at E in Fig. 3, to form lateral passages for the material overflowing from this plane or part of the table.

While I prefer constructing the table in the manner before described, and providing the table with the side discharges, it is not necessary that the sides of the table be cut away as shown at E, but these sides may remain of normal height and openings similar to those shown at G may be made through the table adjacent the vertical sides, as shown in Fig. 8, for the purpose of forming the side discharge.

The inclined plane or portion, A, of the table is a stratifying plane, affording a surface upon which the minerals that flow over it may stratify according to their specific gravities, the heaviest on the bottom and the lightest on top, in which position the particles are progressed forward onto the plane, B, which connects with and forms a continuation of the lower end of the stratifying plane, A, and which plane, B, is a discharge plane, and is preferably level both laterally and longitudinally with the raised outlets, E, formed by cutting away the intermediate portions of the sides opposite or corresponding to the plane, B, as shown in Fig. 3, and as before mentioned. In addition to these overflows, E, the intermediate level plane, B, may be provided at intermediate points in its transverse length with outlets, E', bounded by raised flanges, these outlets serving to receive the overflow of surplus water and waste or tailings which are thrown off in the process of concentration and which are held on the plane, B, as opposed to its progression by an adjacent and succeeding inclined plane, C, which I will presently again refer to.

The flanged or raised outlets, E and E', for the level plane, B, constitute dams of sufficient height to protect the lower stratum of minerals, which is covered with the lighter gangue, and holds it from being washed away with the water and sands as they are carried over in the process of elimination; and as the lower stratum is being continuously advanced toward and up the inclined plane, C, which succeeds the level plane, B, the depth of this mineral stratum can be governed by the speed with which it is progressed, this being controlled by the adjustments provided in a head motion of some appropriate character, it being understood that during the operation of the table the waste material is permitted to pass down through the openings, G, formed between the raised surfaces or dams, E', in the plane, B, to be caught in a suitable trough or launder, L, and which may also serve the overflow, from the side dams, E, and be carried away.

The dams, E and E', with which the plane, B, is provided may be of such length as to afford a much greater overflow surface than is afforded in the width of the incline or plane, A. To illustrate: If the width of the inclined plane, A, is five feet and the depth of the flowing pulp is one quarter of an inch and the overflow dams, E and E', are two and one-half feet long, I would then have eight dams, as shown in Fig. 5, each two and one-half feet long or twenty lineal feet, and as the dams are all of equal height and level, the flow down the inclined plane, A, is equally divided, I would have a depth of overflow of each section of the plane, B, equal to one-quarter of the flow on the plane, A, or in other words, a depth of overflow of about one-sixteenth of an inch. This provision of extra overflow surface is important, particularly when used in association with the intermediate dams, E', of Figs. 2 and 5, and of which there may be any desired number, for at least two reasons. First, by dividing and reducing the depth of the overflow, I avoid rapid currents in any one direction which would cause agitation of the stratified mineral on the surface of the level plane, B, and thereby cause a loss of fine material which would be carried away with the water and waste material as suspended matter: Second, by the introduction of the dams on the plane, B, at proper distances across said plane, I believe any congestion of accumulated gangue at the base of the succeeding incline, C, which might otherwise interfere with the proper progression and dressing of the lower mineral strata, and for other reasons.

The bedded and stratified minerals on the level plane, B, will always maintain a uniform depth across said plane, insuring an even discharge at the overflows or dams, E, E', for the reason that the reciprocating motion imparted to the table by the head-mechanism will have the effect of shaking the immersed sands and minerals to a constant level. This constant stratified condition of the heavier minerals and gangue on the level discharging plane, B, insures a rapid elimination of the top layer of waste matter over the raised overflow dams, E and E', the overflow being laterally in the form of a thin film and in a slowly moving current without disturbing and thereby causing a loss of the lower strata of minerals that are being progressed longitudinally along said plane or planes.

As before stated, the intermediate level plane, B, connects at its lower edge with the succeeding plane, C, which latter plane is inclined upwardly toward the tail end of the machine and is designed to retard or hinder the progression of the material from the plane, B, on to the final inclined plane, D. This latter plane, D, is a dressing plane

upon which is delivered the water discharged from the distributor, H, the said plane, D, being given such degree of inclination as will be best adapted to the proper dressing of the concentrates as they pass over it from the more sharply inclined retarding plane, C, to the tail end of the machine.

The water and all minerals and gangue carried down with it in the dressing process are caught on the level plane, B, where the heavier mineral particles assisted by the reciprocating motion imparted to the table, are given an opportunity to again settle, and be progressed up the incline, C, while the lighter gangue is carried by the combined waters flowing from opposite directions toward the plane, B, from the inclined planes, A, C and D, over the outlets E and E', into some suitable launder, L, or other receiver provided to carry them away.

The plane, C, is a comparatively short plane which lies intermediate of the planes, B and D and is attached to the latter, which is sufficiently flexible to have its inclination altered at pleasure by any well known means, as for instance by an eccentric, 5, bearing under the outer end of the plane. The plane, C, has a fixed sharp or rapidly rising inclination, greater than that given the plane, D, and it joins the level plane, B, at the concentrates discharge end thereof, and thereby forms a sloping wall of such inclination that the sands which usually form the greater portion of the crushed ore or pulp to be concentrated, will be retarded or checked in their progress under the influence of the progressive action of the machine, and owing to the less specific gravity of these sands as compared to their associated minerals, the sands will be carried over the overflow dams, E and E', together with the water in which they are submerged, while the minerals of greater specific gravity and which form the lower strata on the level plane, B, will be forced up and over the plane, C, and onto the final dressing plane, D, thereby effecting the separation of the mineral contents of the ore from the associated rock from which it has been liberated by the process of crushing and fine grinding. Any particles of sand that may be carried over the short plane, C, by the body of advancing minerals, may be washed back onto the level plane, B, by the opposing current of dressing water flowing down the plane, D, which is inclined downwardly toward the plane, B, and substantially oppositely to the inclined plane, A.

By reference to Figs. 2 and 4, it will be observed that the final dressing plane, D, is there provided with parallel channels, D', the purpose of which is to contract the space occupied by the concentrated product passing over the plane, D, thereby expediting the process of dressing with the water

applied to the discharge end of the plane and increasing the speed with which the mineral may be progressed, owing to the greater mass of the channeled bodies.

It will be noted that the pulp is fed on to the table at the end opposite the concentrates discharge, and that the introduction of the feed cannot in any way disturb the process of stratification, agitate the bedded material on the plane, B, or interfere with the prompt settling and recovery of minerals washed back over the retarding plane, C, from the final dressing plane, D.

The stratifying plane, A, is continuously inclined downward from the feed end to its connection with the level plane, B, in order that the process of stratification of the minerals may be more quickly accomplished as the flow of the pulp is reduced to a very thin body which admits of all suspended particles being brought into contact with the surface of the plane or the stratum of sand and minerals covering it as a result of acceleration of the flow due to the inclination of the plane, A, and which latter plane may be made adjustable in order to fix its inclination to that degree which will best serve the purpose; under varying conditions of quantity, or the ratio of solids and liquids of which the pulp being treated is composed, this provision for the adjustment of the stratifying plane, A, may be important. The adjustment of the plane, A, may be accomplished by any well known and desired manner and as one embodiment of this phase of my invention I show eccentrics, 5, on shafts, 6, and adapted to increase or decrease the inclination of the plane, A, according as the eccentric is turned to cause its ascending or descending cam surface to bear under the upper end of the plane, as shown particularly in Figs. 3 and 7.

It will also be noted that the relative positions of the planes, C and D, are fixed as to each other and that any adjustment of the inclination of the plane, D, affects the plane, C, directly in proportion to the relative lengths of these planes, as the point of flexibility lies at the junction of the planes, B and C. The inclination of the plane, C, is such that the heavier minerals only, have sufficient power of inertia to ascend the plane under the impulse of the reciprocating and progressive action imparted to the table by the actuating mechanism.

From the foregoing it will be apparent that the minerals contained in the pulp are stratified on the plane, A; that the heavier minerals will settle to the bottom and the lighter minerals and gangue will remain on top so that when the pulp has reached the level plane, B, the minerals will all have arrived in their stratified form and the lighter portion or waste will be allowed to flow over the dams E and E' while the heavier mineral

will be advanced by the progressive action of the separating mechanism, up the plane, C, to the succeeding dressing plane, D, and the finished product will be delivered over the discharge end of this last-named plane.

There is also provided the novel feature of the side discharge on both sides of an intermediate portion of the table, which permits the further novel function of propelling the mineral up the incline, C, while the waste material is discharged over the dams, E and E', of the level plane, B.

In the use of my improved table, I am not required to tilt the table either laterally or longitudinally, and I dispense with the customary riffles and stratify down the initial incline, A. If, however, it should appear that a tilting of the machine was desirable, it might be accomplished without any substantial alteration in the form of the table surface with the several planes heretofore described. In either instance there is no conflict between the functions of separating the minerals on the one bed and the discharge of the waste matter on the other.

Having thus described my invention what I claim as new and desire to secure by Letters Patent is:—

1. A concentrating table surface composed of a stratifying plane, a succeeding bedding and discharge plane, said bedding and discharge plane having means for discharging the lighter gangue from the table, a resisting plane succeeding the discharge plane adapted to hinder the progression of material received therefrom, and a dressing plane succeeding the resisting plane.

2. A concentrating table surface having an inclined stratifying plane, a discharge plane connecting therewith, said discharge plane being provided with means for discharging the lighter gangue from the table, an inclined resisting plane succeeding the said discharge plane, and a dressing plane with which the inclined resisting plane connects.

3. A concentrating table surface having an adjustably inclined stratifying plane, a discharge plane connecting therewith, said discharge plane being provided with means for discharging the lighter gangue from the table, and an adjustable plane having in succession a resisting section and a dressing section.

4. A concentrating table surface whose lateral position is a constant level, said surface comprising a longitudinally inclined stratifying plane, a discharging plane connecting therewith, said discharge plane having outlets for the discharge of lighter gangue from the table, and longitudinally inclined resisting and dressing planes succeeding the discharging plane and connecting therewith and with each other.

5. A concentrating table surface whose lateral position is a constant level, said sur-

face comprising a longitudinally inclined stratifying plane, a discharge plane connecting therewith, said discharge plane having outlets for the discharge of the lighter gangue from the table, and a longitudinally inclined adjustable plane having in succession a resisting section and a dressing section.

6. A concentrating table surface comprising a stratifying plane, a succeeding bedding and discharge plane, and successive resisting and dressing planes, said discharge plane being provided with side and intermediate openings for the discharge of lighter gangue from the table, and vertical flanges bounding and protecting said openings.

7. A reciprocating concentrating table surface comprising a stratifying plane, a succeeding bedding plane, said bedding plane having openings and flanges adjacent thereto forming protecting dams, said flanges being of equal height and positioned longitudinal to the line of motion and admitting of the lateral discharge of lighter gangue from the table, simultaneously with the discharge longitudinally of the protected lower strata of heavier minerals, and a plane succeeding the bedding plane having in succession a resisting section and a dressing section.

8. A concentrating table surface comprising a stratifying plane, a discharge plane, said discharge plane having means for discharging lighter gangue from the table, an inclined dressing plane, and an inclined resisting plane connecting with the discharge plane and forming a part of the dressing plane, and of a different angle of fixed inclination.

9. A concentrating table surface comprising a stratifying plane, a bedding and discharge plane and an adjustably inclined combined resisting and dressing plane succeeding the bedding and discharge plane, said last-named plane being provided with means for discharging lighter gangue from the table, and means for maintaining the inclination of the resisting plane always in direct proportion to the inclination of the dressing plane.

10. A concentrating table, comprising a stratifying plane, a succeeding bedding and discharge plane, said discharge plane having means for discharging the lighter gangue from the table, and an adjustably inclined plane succeeding the bedding and discharge plane and having in succession a resisting section and a dressing section, and having a corrugated surface.

11. A concentrating table, comprising a stratifying plane, a succeeding bedding and discharge plane, said discharge plane having means for discharging the lighter gangue from the table, and an adjustably inclined plane succeeding the bedding and discharge plane and having in succession a resisting

section and a dressing section, and having a corrugated surface, with the corrugations extending longitudinally to the flow of material thereover.

- 5 12. A concentrating table, comprising a stratifying plane, a succeeding bedding and discharge plane, said last-named plane having means for discharging lighter gangue from the table, an inclined resisting plane
10 succeeding the bedding and discharge plane, and a dressing plane succeeding the resisting plane, said dressing plane being longitudinally channeled, and means for maintaining the inclination of the resisting plane
15 always in direct proportion to the inclination of the dressing plane.
13. A concentrating table surface composed in part of an adjustably inclined plane having in succession a resisting section and

a dressing section, the different angles of inclination of each of said sections being permanently fixed as to the other at any degree of adjusted inclination of said plane.

14. A concentrating table surface composed of a stratifying plane, a discharging plane having an overflow discharge for the lighter material, a resisting plane, and a dressing plane, the receiving and major portion of the stratifying plane, the upper or delivery portion of the resisting plane, and all of the dressing plane lying above the overflow level of the discharging plane.

In testimony whereof I affix my signature in presence of two witnesses.
